GRINDING MACHINE

Cecil W. Hopkins, Cincinnati, Ohio, assignor to
 Cincinnati Grinders Incorporated, Cincinnati,
 Ohio, a corporation of Ohio

Application August 18, 1930. Serial No. 475,929

16 Claims. (Cl. 51—103)

This invention relates to improvements in machine tools and especially to improvements in centerless grinders.

One of the principal objects of the present invention is the provision of an improved automatic centerless grinder for effecting grinding operations on tapered or other formed work pieces.

Another object of the invention is the provision of a centerless grinder for performing grinding operations on successive formed work pieces in a substantially continuous stream thereby reducing idle time of the machine to a minimum and increasing the production to the maximum.

Another object of the invention is the provision of improved means for feeding, positioning and discharging work pieces from the grinding throat of a centerless grinder.

Another object of the invention is the provision of a centerless grinder for the production of work pieces that is automatic in its action requiring no attention of the operator other than supplying additional work pieces to the magazine or hopper.

Other objects and advantages of the present invention should be readily apparent by reference to the following specification considered in conjunction with the accompanying drawings forming a part thereof, and it is to be understood that any modifications may be made in the exact structural details there shown without departing from or exceeding the spirit of the invention as defined in the claims appended hereto.

35 In the drawings:

Figure 1 is an elevational view of a grinding machine embodying the improvements of this invention.

Figure 2 is a top plan view of the device shown in Figure 1.

Figure 3 is an enlarged fragmentary sectional view taken on line 3—3 of Figure 2, showing the grinding throat with the work supplying means in position.

Figure 4 is a view taken on line 4—4 of Figure 1, certain parts being in elevation and other in section.

Figure 5 is a sectional view taken on line 5—5 of Figure 4.

Figure 6 is a sectional view taken on line 6—6 of Figure 4.

Figure 7 is a sectional view taken on line 7—7 of Figure 2.

Figure 8 is a sectional view taken on line 8—8 of Figure 7.

Figure 9 is a sectional view taken on line 9—9 of Figure 8.

Figure 10 is a sectional view on line 10—10 of Figure 8.

Throughout the several views of the drawings similar reference characters are employed to denote the same or similar parts.

A device embodying the improvements of this invention may comprise a bed or support 10 supporting for rotative movement at a high or grinding rate of speed at one end thereof a grinding wheel 11 rotatable in a clockwise direction as indicated by the arrow on its housing. Opposed to the grinding wheel 11 is a regulating wheel 12 rotatably supported by regulating wheel unit 13 for rotation in a clockwise direction at a slow work controlling rate of speed. The opposed surfaces of the wheels 11 and 12 form therebetween a grinding throat adapted to receive a work piece therein for simultaneous action thereon by the said wheels. The regulating wheel unit 13 is integral with a slide 14 movable on ways 15 formed on the upper surface of a second or lower slide 16. The said lower slide 16 is likewise movable longitudinally of the bed 10 on ways 17 formed on the said bed. Clamps 18 and 19 are provided for respectively securing the upper slide 14 to the lower slide 16 and the said lower slide 16 to the bed. Translation of the said slides is accomplished through an adjusting screw 20 rotatably journaled in a housing 21 and having on its outer end a pilot or hand wheel 22. The threads of the screw 20 engage with a nut 23 carried by the unit 13. The said slides 14 and 16 are adjusted by the pilot or hand wheel 22 to position the wheels 11 and 12 relative to one another to provide a grinding throat of the desired size at the time the machine is being initially setup and to take care of wheel wear and the like on the said wheels.

Mounted on the lower slide at its forward end beneath the grinding throat is a block 24 supporting a work rest blade 25 having an angled top 26 inclining toward the active face of the regulating wheel and forming a work trough thereby. The block 24 in addition supports adjacent the grinding throat a work supporting table 27 which is intermediate the grinding throat and the feeding mechanism mounted within housing 28 and likewise carried by the block 24. On the other side of the grinding throat, supported by the block 24, is the stop or work limiting mechanism carried by the bracket 29.

As shown in Figure 3, the work carrying mecha-

110

nism 27 includes an inclined table 30 having at one end thereof a positioning rib 31 against which one end of the work abuts, as shown in Figure 2. The table 30 terminates in a downwardly extending portion 32 which forms one wall of a vertical magazine. The other wall of which is formed by angle irons 33 and 34 adjustably secured to vertical brackets 35. The angle irons 33 and 34 are each provided with elongated 10 perforations 36 so that the said angle irons may be adjusted toward and from the vertical wall 32 to vary the capacity of the magazine. Beneath the magazine is an angled top support 37 carried by the block 24 and in substantial 15 alignment with the angled top 26 of the work rest blade 25.

The work feeding mechanism within the housing 28 comprises an oscillatable arm 38 mounted for movement about a sleeve 38a loosely mounted 20 on and co-axial with the rock shaft 39. The said shaft 39 is keyed or otherwise secured to an actuator 40 which has secured thereto one end of a spring 42 having its other end connected with a pin 43 fixed to one wall of the housing 25. The actuator 40 has an arcuate slot 41 formed therein through which a pin or bolt 41a passes for connecting the actuator 40 and arm 38 with one another in various adjustments. The upper end of the arm 38 is forked to provide fingers 44 and 45, as seen in Figure 5, 30 straddling the guide member 46. The fingers 44 and 45 are each in turn bifurcated to provide ears 47 and 48 between which rollers 49 are received. The rollers 49 extend from opposite sides of the guide 46 and are rotatably mounted on pins 50 extending from block 51 through elongated openings 52 formed in the sides of guide member 46. The block 51 is formed on the end of a plunger 53 which has in its forward end a tapered socket 54 receiving the tapered end or shank of push rod 55. The plunger 53 is guided by bearings 56 mounted within guide sleeve 57 secured to one end of housing 28. A closure tube 58 is threadedly carried by the guide sleeve 57 40 to protect the operator and plunger from injury. As seen from Figure 3, the lowermost work piece 59 is lying on the support blade 37 with one end of plunger rod 55 abutting same, as shown in Figure 4. Rocking of the actuator 40, by means 50 to be later described, will oscillate arm 38 and block 51 thereby axially shifting plunger 53 and push rod 55 to the rear and loading the spring 42. Subsequently or at the completion of the 55 grinding operation the said spring 42 expands or fires for reversely, axially shifting the plunger 53 and push rod 55 for injecting the said lowermost work piece into the grinding throat onto the angled face 36 of work rest blade 25. The lower end 60 of side bracket 35 60 is spaced above the upper surfaces of support blade 37 and work rest blade 25 a distance sufficient to permit the movement of the lowermost work piece thereunder but prevent any movement of the next adjacent work piece. 65 The work pieces are machined or finished with a taper from one end to the other for which purpose the active face of the regulating wheel is tapered an amount double the taper to be formed on the said work thereby permitting the grinding 70 wheel to have a plane face. This taper is of a very small amount and is not shown in the drawings, it being no greater than that produced on twist drills and the like with which those conversant with this art are familiar. In order to 75 position the work properly relative to the said

faces of the wheels a stop or positioning mechanism is provided. This mechanism comprises the bracket 29 supporting a bracket 61 adjustably carrying an overhead guide shoe 62 adjustable by bolts 63 extending through elongated openings 64 into the bracket 61. The stop or positioning member 65 has a rack 66 extending therefrom and meshing with an elongated pinion 67. The pinion 67 is fast on shaft 68 journaled in the walls of the bracket 29. A second rack bar 69 is provided and is adapted to be actuated in a plane at right angles to the plane of movement of the rack 66 and the said rack 69 engages with the pinion 67 for actuating said pinion. The shifting movement of rack bar 69 is obtained through an arm 70 having a sliding connection at 71 with a block 72 adjustably secured to the bar 69. The said arm 70 is pivoted at 73 to the bracket 29 and is oscillatable thereabout by an actuating rod 74 slidably journaled in bearings 75 and 76 extending from the block 24. A spring 77 surrounds the actuating rod 74 abutting on one end with the bearing 75 and on the other end with the collar 78 secured to the rod 74. The shifting movement is imparted to rod 74 by a trigger 79 keyed for movement with oscillatable or rock shaft 80. The said rock shaft 80 is actuated in synchronized relation with the rock shaft 39 by the mechanism to be later described.

After the work piece has been positioned within the grinding throat the said throat is contracted or restricted as by actuating the regulating wheel unit 13 and slide 14 toward the grinding wheel to shift the work on the blade 25 into the grinding wheel and effect a stock removal therefrom. This movement is accomplished automatically by the mechanism within housing 21 which includes the worm shaft 81 having removably secured on its one end a gear 82 coupled through pick-off gears 83 to the motor 84 secured to the lower end of the housing 21. The shaft 81 has secured thereto or integral therewith a worm 85 meshing with a worm wheel 86 on a shaft 87 which has keyed on one end thereof a cam plate 88 having the cam groove 89 formed in one face in which roller 90 is received. The roller 90 is carried by an adjustable block 91 in turn secured to an arm 92 pivoted at 93 to the wall of the housing 21. The arm 92 has a portion 94 extending above the pivot 93 from which lugs 95 extend and have pivoted thereto one end of links 96. The other end of links 96 are pivoted to a slide block 97 100 slidable through bearing 98 and secured to the adjusting screw 20 as by collars 99.

From the foregoing it will be noted that rotation of cam 88 through cam groove 89 effects a rocking or oscillating movement of the arm 92-94 about the pivot 93. This oscillating movement through the links 96 actuates the slide block 97 105 and adjusting screw axially relative to the bearings thereby actuating the regulating wheel unit 13 and wheel 12 toward and from the grinding wheel. This movement is accomplished through the sharp rise 100 which effects a rapid in-feed 110 movement of the unit 13 followed by a gradual rise from the point 101 to point 102 for slowly feeding the work into the grinding wheel and then a concentric portion from point 102 to point 103 at which time the parts are held relatively 115 stationary to permit a sparking out of the grinding wheel and the desired finish on the work. A sharp decline from point 103 to point 100 then comes into play for rapidly retracting the regulating wheel unit 13 to the work loading position. 120

It is when the said wheel is retracted that the finished work is discharged from the grinding throat and an unfinished one placed therein.

This shifting of the work into and out of the grinding throat is performed in synchronized timed relation with the movement of the unit through the rock shafts 80 and 39. The said rock shafts, as shown in Figure 1, extend from the housing 28 to the housing 21 being journaled therein and actuated by the cam 88. The rock shaft 80 has its rear end journaled in the wall of the housing 21 on which a rack pinion 104 is secured for movement therewith. Meshing with the pinion 104 is a slideable rack bar 105 having a lug 106 formed at one end thereof. One end 107 of a lever 108 engages with the lug 106 and has its other end pivoted at 109 to a lug 110 carried by the wall of the housing 21. The lever 108 has rotatably secured thereto intermediate its ends a roller 111 riding on the rear face 112 of the cam 88. A cam portion or lug 113 is formed on the said face 112 for engaging the roller 111 and actuating arm 108 about its pivot 109.

The forward face 113 of cam 88 is provided with a depression 114 for receiving a roller 115 riding on the said face 113. This roller 115 is carried by the inner end of sliding rack bar 116 which has its teeth meshing with rack pinion 117 journaled in a bracket 118 extending from the housing 21. The said bracket 118 supports the sliding bearing for the sliding rack bar 116 as well as forms the bearings for oscillatable shaft 39.

The cam portion in cam groove 89 between the points 103, 100 and 101 and the depressed cam portion 114 on one face of the cam 88 and the cam lug 113 on the other face thereof are so related that the depressed portion of the cam 103—101 first retracts the regulating wheel unit from the grinding wheel whereupon cam lug 113 actuates the arm 108 for rocking shaft 80 and raising stop 65 out of the path of the work piece within the grinding throat and then the cam depression 114 aligns with roller 115 when spring 42 will rock the shaft 39 forcing the said roller 115 into the depression 114 thereby axially shifting plunger 53 and push rod 55 for shifting the lowermost work piece in the magazine into the grinding throat which work piece pushes the finished work piece therein ahead of its past the end of the work rest blade 25. As the finished work piece passes over the edge of the blade it becomes top heavy falling off of said blade into a suitable receptacle or the like. At this time the cam lug 113 rides from under the roller 111 and the spring 77 which surrounds the rod 74 having been compressed or placed under tension during the raising of the abutment member 65, now expands and lowers said abutment into the path of movement of the unfinished work piece being placed within the grinding throat by the pusher 55 to position said work relative to the wheels. As soon as the work piece has been properly positioned the roller 115 is ejected from the cam depression 114 by the walls thereof and the rod 116 through the rack and pinion connection rock the rock shaft 39 in a counter-clockwise direction for withdrawing the pusher 55 from the grinding throat and loading the actuating spring 42. This retraction of the pusher 55 permits the lowermost work piece in the magazine to fall onto the support blade 37 in the path of movement of the pusher 55. At the same time or during the retraction of the pusher 55 the cam 88 has advanced to the position for the rapid infeed of the regulating wheel 12 and slide 14 toward the grind-

ing wheel to initially feed the work into the grinding wheel whereupon the further movements of the regulating wheel unit are under the control of cam 88, as above described, until the completion of the grinding operation.

From the foregoing it will be noted that an automatic form grinding machine has been provided whereby the only attention necessary by the operator is the placing of unfinished work pieces or blanks on the inclined table member 30 which pieces, under the influence of gravity, roll down the said table member to the hopper or magazine at the end thereof, the work pieces stacking one upon the other in a vertical column. Through the cam member 89 the lowermost work piece in the magazine is positioned within the grinding throat pushing ahead of it the finished work piece therein whereupon the stop mechanism finishes the positioning of the work piece relative to the active face of the wheels. After the work has been positioned the grinding throat is retracted to feed the said work into the grinding wheel and effect a stock removal therefrom whereupon the throat is widened and a recurrence of the loading cycle automatically initiated.

It will be noted that the work is yieldingly fed into the grinding throat so that should an obstruction enter the path of the work or a jam occur no breakage or damage to the parts will result since the feeding will be held in abeyance 105 against the yielding action of the feeding spring 42.

What is claimed is:

1. In a centerless grinder the combination of a pair of opposed grinding and regulating wheels forming a grinding throat therebetween, a work rest blade within the grinding throat for supporting work pieces in simultaneous engagement with the said wheels, a magazine for holding work pieces exteriorly of the grinding throat in alignment therewith, means for axially individually shifting the work pieces from the magazine into the grinding throat, said axially shifted work piece displacing the finish work piece within the grinding throat, and means co-operating with the work rest blade for positioning the work relative to the wheels but movable relative to the blade to permit the finished work to pass thereunder while being discharged from the grinding throat.

2. In a device of the class described the combination of a bed or support, a pair of opposed grinding and regulating wheels carried thereby and forming a grinding throat therebetween, a work rest blade within the throat and supporting work while in engagement with the wheels, a magazine adjacent the throat exteriorly thereof, a support member beneath the magazine in alignment with the work rest blade, means operable toward the grinding throat for shifting the lowermost work piece from the magazine support onto the work rest blade, abutment means for engaging the work to position same relative to the work rest blade, and means for shifting the abutment means out of the path of the work to permit the said work to pass thereby as it is being discharged from the grinding throat.

3. In a device of the class described the combination of a bed or support, a pair of opposed grinding and regulating wheels carried thereby and forming a grinding throat therebetween, a work rest blade within the throat and supporting work while in engagement with the wheels, a magazine adjacent the throat exteriorly thereof, a supporting member beneath the magazine in alignment with the work rest blade, means op-

- erable toward the grinding throat for shifting the lowermost work piece from the magazine support onto the work rest blade, abutment means for engaging the work to position same relative 5 to the work rest blade, means for actuating one of the wheels toward and from the other to effect a stock removal from the work within the grinding throat and to replace the finished work within said throat, and means operable in time relation with the movement of said wheel for retracting the abutment means from the path of movement of the work as it is being discharged from the grinding throat.
4. In a centerless grinder for automatically 15 grinding formed work pieces or the like comprising opposed grinding and regulating wheels forming a grinding throat therebetween, a work rest blade within the throat supporting work pieces in engagement with the said grinding and regulating wheels, means for axially feeding unfinished work into position between the said wheels on the work rest blade and for axially discharging the finished work from said blade, means for contracting the grinding throat to 20 effect a stock removal from the work piece, and retractable positioning means cooperating with the feeding means to permit the finished work to pass thereby and subsequently positionable to engage the unfinished work for properly positioning the said unfinished work relative to the wheels.
5. A feeding mechanism for feeding successive work pieces through the throat of a centerless grinder comprising means supporting the said work pieces relative to the grinding throat exteriorly thereof, a pusher abutting said work and pushing same into the grinding throat, an abutment aligned with the grinding throat limiting the movement of the work through the throat, 35 and means retracting the abutment out of the line of movement of the work to permit the discharge of the work piece from the throat by the pusher.
6. An abutment mechanism for positioning work pieces relative to the work rest blade of a centerless grinding throat comprising a bracket, 45 a stop block carried by the bracket and movable relative thereto, means for positively raising the stop block from the path of movement of the work to permit discharge of the work from the grinding throat, and yielding means for returning the stop block to its operative position for positioning a succeeding work piece.
7. In a centerless grinder the combination of 50 a pair of opposed grinding and regulating wheels forming a grinding throat therebetween, a work rest for supporting work pieces within the grinding throat, means for moving one of said wheels toward the other to feed the work piece into the grinding wheel, means for axially shifting work pieces into the grinding throat and axially ejecting them therefrom, an abutment member for engaging the work shifted into the grinding throat for positioning same relative to the wheels but retractable from the path of movement of the work to permit a discharge of the work from the grinding throat, and a single cam member for actuating said parts in timed sequential order.
8. In a device of the class described the combination with means for feeding work pieces into and through the throat of a centerless grinder, 55 of an abutment shoe for positioning the work relative to the throat, a rack bar extending from the shoe, a rack pinion meshing with the rack bar, a second rack bar engaging the rack pinion, and means for actuating the second rack bar and raising the abutment shoe through the rack and pinion connection thereof out of the path of movement of the work being discharged.
9. In a device of the class described the combination with means for feeding work pieces into and through the throat of a centerless grinder, 60 of an abutment shoe for positioning the work relative to the throat, a rack bar extending from the shoe, a rack pinion meshing with the rack bar, a second rack bar engaging the rack pinion, means for actuating the second rack bar and raising the abutment shoe through the rack and pinion connection thereof out of the path of movement of the work being discharged, and additional yielding means for lowering the abutment shoe to its normal position for engaging succeeding work pieces.
10. In a device of the class described the combination with means for feeding work pieces into and through the throat of a centerless grinder, 65 of an abutment shoe for positioning the work relative to the throat, a rack bar extending from the shoe, a rack pinion meshing with the rack bar, a second rack bar engaging the rack pinion, means for actuating the second rack bar and raising the abutment shoe through the rack and pinion connection thereof out of the path of movement of the work being discharged, and additional yielding means for lowering the abutment shoe to its normal position for engaging succeeding work pieces.
11. In a device of the class described the combination with means for feeding work pieces into and through the throat of a centerless grinder, 70 of an abutment shoe for positioning the work relative to the throat, a rack bar extending from the shoe, a rack pinion meshing with the rack bar, a second rack bar engaging the rack pinion, means for actuating the second rack bar and raising the abutment shoe through the rack and pinion connection thereof out of the path of movement of the work being discharged, said means comprising a rock shaft, a sliding shaft, an operative connection between the rock shaft and sliding shaft for actuating the latter by the former, and a pivoted arm operatively connected with the second rack bar and actuated by the sliding shaft for adjusting said second rack 75 bar and elevating the abutment shoe.
12. In a device of the class described the combination with means for feeding work pieces into and through the throat of a centerless grinder, 80 of an abutment shoe for positioning the work relative to the throat, a rack bar extending from the shoe, a rack pinion meshing with the rack bar, a second rack bar engaging the rack pinion, means for actuating the second rack bar and raising the abutment shoe through the rack and pinion connection thereof out of the path of movement of the work being discharged, said means comprising a rock shaft, a sliding shaft, an operative connection between the rock shaft and sliding shaft for actuating the latter by the former, a pivoted arm operatively connected with the second rack bar and actuated by the sliding shaft for adjusting said second rack bar and elevating the abutment shoe, and yielding means surrounding the sliding shaft adapted to be tensioned by 85 the movement thereof for returning the abutment to its normal position after discharge of the work.
13. In a centerless grinder the combination of a bed, a pair of opposed grinding and regulating 90 wheels forming a grinding throat therebetween, a work rest blade subtending the grinding throat and supporting the work piece in simultaneous engagement with the said wheels, one of said wheels being mounted for sliding movement toward and from the other wheel, a magazine exteriorly of the grinding throat and in alignment therewith, a pusher member for shifting work pieces from the magazine onto the work rest blade, an abutment for engaging the work 95 piece and positioning it relative to the work rest blade, a rock shaft for actuating the pusher, a second rock shaft for retracting the abutment member whereby the work piece may pass there-by when being discharged from the work rest 100.
